CLAIM

The ornamental design for an air valve cap, as shown and described.

DESCRIPTION

FIG. 1 is a top, front and right side perspective view of an air valve cap, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another perspective of the air valve cap showed in its disassembled state.

The broken lines show the features of the air valve cap and environmental subject matter that form no part of the claimed design.
